(57) **CLAIM**

The ornamental design for a suturing device, as shown and described.

DESCRIPTION

FIG. 1 is a perspective view of a suturing device in accordance with the present invention;

FIG. 2 is a side view of the suturing device of FIG. 1; FIG. 3 is a side view of the opposite side of the suturing device of FIGS. 1 and 2;

FIG. 4 is a top view of the suturing device of FIGS. 1-3; FIG. 5 is a bottom view of the suturing device of FIGS. 1-4; FIG. 6 is a front view of the suturing device of FIGS. 1-5; FIG. 7 is a back view of the suturing device of FIGS. 1-6; and,

FIG. 8 is a perspective view of the suturing device of FIGS. 1-7 from a side opposite to the perspective view of FIG. 1. The broken lines are directed to environmental structure and unclaimed subject matter and are for illustrative purposes only; the broken lines form no part of the claimed design.
